METHOD AND APPARATUS FOR MAKING
DISHED HEADSCharles B. Cuswhwa and Thomas C. Kane,
Youngstown, Ohio

Application April 11, 1940, Serial No. 329,122

4 Claims. (Cl. 29—33)

This invention relates to the manufacture of dished heads.

Dished heads are used extensively in the manufacture of tanks and have usually been made heretofore by pressing or by spinning over a mold. Both these methods are objectionable for various reasons. Presses capable of shaping large heads cold are very expensive and the shaping of heads while hot involves the cost of furnace equipment. The method of spinning heads over molds requires that a large number of molds of various sizes and shapes be kept in stock and these molds represent a substantial investment.

We have invented a novel method and apparatus for making dished heads whereby the aforementioned objections to previous methods are entirely overcome. In a preferred practice of our invention, we provide a blank, preferably substantially circular, and reduce the thickness of an annular zone thereof spaced inwardly from the edge. This reduction is accompanied by a radial spreading of the material of the blank. The reduction may be effected by rolling or otherwise, and causes the edge portion of the blank to be dished laterally from its original plane. By this method, heads of various sizes and various degrees of curvature may be made easily and quickly.

For carrying out our method, we have provided apparatus including a rotatable support for the blank having blank-holding means, and a traveling roll adapted to roll down or thin an annular zone spaced inwardly from the edge of the blank. We also provide means for flanging the edge of the head after it has been suitably dished.

The method of our invention will be more fully explained and the apparatus described in detail hereinafter by reference to the accompanying drawings illustrating a preferred embodiment and practice. In the drawings,

Fig. 1 is a transverse sectional view through our apparatus, with parts in elevation;

Fig. 2 is a horizontal sectional view taken along the plane of line II—II of Fig. 1; line I—I of Fig. 2 illustrates the plane of the section shown in Fig. 1; and

Fig. 3 is a partial sectional view taken along the plane of line III—III of Fig. 1.

Referring in detail to the drawings, our apparatus comprises a base 10 having upstanding columns 11 and 12 adjacent the ends thereof. These columns may conveniently be castings of box section. The base 10 and the columns 11 and 12 are secured in any convenient manner to a suitable foundation 13. Transverse webs 14 and 15

in the base provide bearings for a supporting roll 16. As shown in the drawings, the web 14 is disposed substantially centrally of the base 10. A motor-reducer unit 17 mounted on the base 10 drives the roll 16 through spur gearing 18.

Transom rails 19 extend between the columns 11 and 12 above the base 10. A clamp-supporting bracket 20 is secured to the rails 19 substantially centrally thereof. The bracket 20 supports a vertically disposed fluid-pressure cylinder and piston 21 including a piston rod 22. The rod 22 has a foot 23 rotatable thereon adapted to cooperate with a thrust bearing 24 on the web 14 to support a plate or blank, the initial position of which is indicated at 25, in position to engage the roll 16.

A carriage 26 is slidable along the rails 19. A screw shaft 27 journaled in the column 12 and bracket 20 cooperates with a nut 28 in the carriage for reciprocating the latter along the rails. A motor-reducer unit 29 mounted on a bracket 30 secured to the column 12 drives the shaft 27 through spur gearing 31.

The carriage 26 is provided with a vertically movable slide 32. A roller 33 is journaled in the lower end of the slide for engagement with the blank 25. As shown in Fig. 2, the axes of the roll 16 and the roller 33 lie substantially in the same vertical plane.

The slide 32 may be adjusted vertically by any convenient means. As an example, we have shown a rack bar 34 on the slide meshing with a pinion 35 on a shaft 36 journaled in the carriage 26. A hand-wheel 38 on the shaft 35 permits the slide 32 to be raised or lowered.

The base 10 has an inwardly extending web 39 and guides 40 extend from this web to the adjacent end of the base. A carriage 41 is slidable on the guides 40 and is provided with a slide 42.

The carriage is adjusted by a screw shaft 43 journaled in the column 11 and the web 39, which cooperates with a nut 44 in the carriage. The slide 42 is adjusted vertically by means of a jack screw 45 depending from a lug 46 on the slide.

The jack screw 45 is threaded through a worm wheel 47 disposed within a pocket in the carriage 41. A worm shaft 48 journaled in the column 11 and the web 39 has a worm 49 thereon meshing with the worm wheel 47. A motor-reducer unit 50 drives the shaft 48 through spur gearing 51.

A roll shaft 52 is journaled vertically in the slide 42 and a shaping roll 53 is removably disposed on the upper end of the shaft.

A carriage 54 is slidable on the rails 19 between the column 11 and the bracket 20. This

carriage is provided with a vertically movable slide 55. A shaft 56 journaled in the column 11 and the bracket 20 has a pinion 57 splined thereon. The pinion meshes with a rack 58 on the slide 55 whereby the slide may be adjusted vertically on rotation of the shaft 56 as by a crank 59. A roll shaft 60 is journaled vertically in suitable bearings in the slide 55. The shaft has a roll body 61 thereon. A shaping head 62 is removably secured to the roll body 61.

A motor-reducer unit 63 on the carriage 54 drives an elongated pinion 64. A gear 65 on the upper end of the shaft 60 meshes with the pinion 64 whereby the unit 63 drives the roll 61 in the various positions of the slide 55.

A screw shaft 66 journaled in the column 11 and the bracket 20 cooperates with a nut 67 disposed in a pocket formed in the carriage 54 and is effective to cause traversing movement of the carriage. The carriage is so constructed that pinion 57 moves with it.

Our method of making dished heads by the aid of the apparatus above described, contemplates the disposition of a blank such as that shown at 25 on the thrust bearing 24 and supporting roll 16. The slide 32 on the carriage 26, the slide 42 on the carriage 41, and the piston rod 22 are retracted before the plate is placed on the thrust bearing and supporting roll. The plate 25 is preferably in the form of a substantially circular blank, but means for trimming a square plate to circular form may be incorporated in the apparatus if desired. When the blank has been positioned substantially centrally on the thrust bearing 24, fluid pressure is admitted to the cylinder 21 to advance the piston rod 22 and cause the foot 23 to clamp the blank in position. The motor-reducer unit 17 is then operated to drive the roll 16. The carriage 26 is then adjusted to about the position in which it is shown and the slide 32 lowered until the roller 33 engages the blank. When sufficient pressure is exerted by the roller 33 on the blank 25, the rotation of the roller 16 will cause the blank to revolve about the axis of the piston rod 22 and thrust bearing 24. When the blank is being revolved in this manner, the application of further pressure thereto by the roller 33 will effect a thinning of an annular zone of the surface of the blank spaced inwardly therefrom, accompanied by a radial spreading of the material of the blank. The carriage 26 is preferably adjusted inwardly as this thinning and spreading occurs, to distribute it over an annular zone of substantial width.

The effect of the thinning and spreading of the annular zone spaced inwardly from the edge of the blank is to dish the edge out of the original plane of the blank, as indicated at 68. This result follows necessarily because the periphery of the blank remains unaltered and the thinning and spreading of the annular zone spaced inwardly therefrom increases the area of the plate and has the same relative effect as would be produced by a contraction of the periphery.

By suitably manipulating the slide 32 and the carriage 26, the desired degree of thinning and spreading may be effected to secure the desired curvature or dishing of the blank. When this has been accomplished, the slide 32 is raised. The flanging rolls 53 and 61 are then brought into action by raising the slide 42 and shifting the carriage 41 inwardly to the desired extent. By similar adjustment of the carriage 54 and the slide 55, the desired cooperation between the

rolls 53 and 61 may be effected to bend the edge of the dished blank inwardly to form a flange for attachment to the shell of a tank as by welding or riveting. During the flanging operation, 5 the motor-reducer unit 63 is operated to drive the roll 61 and this causes the blank to revolve so that the flanging is effected progressively. The roll 16 may or may not be continued in operation during the flanging.

10 The head 62 of the roll 61 is shaped to provide the desired radius of curvature between the flange as finally formed and the body of the dished head. After the flanging has been completed, the dished head may be trimmed circumferentially by suitable means, not shown.

15 It will be apparent that the extent of dishing effected is dependent upon the amount of thinning and spreading of the annular zone of the blank spaced inwardly thereof. For this reason, 20 it is possible to shape blanks of various sizes to different degrees of curvature on the same apparatus. The manipulation of the rolls 53 and 61 which is necessary to effect the flanging operation is obvious, and requires no further description. 25 These rolls may be adjusted horizontally and vertically by the various adjusting shafts to bring them into proper cooperative relation.

When the flange has been formed, the rolls 53 and 61 are retracted and the clamping foot 30 23 is raised so that the completed head is free for removal from the apparatus.

It will be apparent that the invention is characterized by numerous advantages over previous methods and apparatus for making dished heads.

35 The apparatus is relatively simple and inexpensive and may be employed to produce a wide variety of shapes and sizes of heads. The cost of expensive presses and the complications incident to hot shaping are entirely avoided, as well 40 as the necessity for maintaining a supply of molds or forms for each different size or shape of head.

Although we have illustrated and described but a preferred embodiment and practice of the invention, 45 it will be understood that changes in the construction and operation disclosed may be made without departing from the spirit of the invention or the scope of the appended claims.

We claim:

50 1. In a method of making dished heads, the steps including providing a substantially flat plate, thinning the plate along a generally circular path spaced inwardly of the edge of the plate, spreading the material in said path radially, 55 thereby causing the material adjacent said edge to dish out of the general plane of the original plate, and thereafter bending up the edge of the plate.

2. In a method of making dished heads, the 60 steps including providing a substantially flat, circular plate, thinning the plate in an annular zone spaced inwardly of the edge thereof, spreading the material in said zone radially, thereby dishing said edge out of its original plane, and 65 thereafter bending up the edge of the blank.

3. Apparatus for dishing heads comprising 70 means securing a blank in position for rotation about a substantially central point, a supporting roll disposed radially of the blank, the periphery of the roll being in contact with the blank, a working roll adapted to engage the side of the blank opposite to which engages the supporting roll, and auxiliary working rolls movable toward and from said blank and radially thereof, 75 effective to turn up a flange around said blank.

4. Apparatus for dishing heads comprising means securing a blank in position for rotation about a substantially central point, a supporting roll disposed radially of the blank, the periphery of the roll being in contact with the blank, a working roll adapted to engage the side of the blank opposite that which engages the support-

5 ing roll, and auxiliary working rolls journaled for rotation on substantially vertical axes movable toward and from said blank and radially thereof, effective to turn up a flange around said blank.
